FLASH LAMP

George W. Cressman, Chagrin Falls, Ohio, assignor to
General Electric Company, a corporation of New York
Filed Oct. 5, 1952, Ser. No. 223,606
1 Claim. (Cl. 67—31)

This invention relates in general to flash lamps of the type comprising a sealed radiation transmitting envelope containing a quantity of combustible light producing material in a combustion supporting medium, such as an oxygenous gas which enters into a reaction with the combustible material with the resulting emission of an instantaneous flash of actinic light of high intensity. More particularly, this invention relates to a flash lamp which generates light for a duration of time on the order of several seconds.

In photography, the need exists for a self contained light source such as a flash lamp which produces light over a time interval sufficient to permit time exposures or an extended sequence of pictures. It is therefore an object of this invention to provide an improved flash lamp having a self contained quantity of light giving combustible material in which the rate of combustion is controlled so that the light output extends over an extended time interval in the range of several seconds.

Moreover, the average movie picture taker photographs sequences of approximately 7 to 10 seconds' duration. Therefore another object of this invention is to provide a flash lamp which emits light of sufficient duration to permit such a sequence to be taken. This duration of light emission must be at a sufficiently high level to provide the taking of movies with the presently available film. Therefore, it is another object of this invention to provide a movie flash lamp which provides a continuous emission of at least 10,000 lumens for a time period on the order of from 7 to 10 seconds.

In accordance with the above-mentioned objects, the preferred embodiments of the invention provides a movie flash lamp which comprises a sealed envelope containing means for emitting at least 10,000 lumens for a time interval on the order of 7 to 10 seconds, said means including a combustible sheet consisting essentially of magnesium having combustion-regulating tabs extending therefrom disposed in a combustion-supporting mixture of approximately 33% argon and 67% oxygen and means for igniting the said combustible sheet.

In the drawing, FIG. 1 shows a flash lamp made in accordance with this invention,

FIG. 2 is a side elevation of part of the mount, and
FIG. 3 is a section view of the mount taken along line
3—3 of FIG. 1.

As shown in FIG. 1, the flash lamp comprises a glass envelope 3 having secured thereto by cement 4 a screw-type base 5. The envelope 3 has fused thereto a glass stem 6 enclosing a pair of lead-in wires 7. The lead-in wires 7 support at their upper ends a filament 9 preferably consisting of a short length of fine tungsten wire having a diameter of the order of 0.7 mil. The inner ends of leads 7 are provided with primer beads 10 of a suitable fulminating material. The lead-in wires are provided with inner end portions 11 bent at an angle to the major portion of the lead-in wires 7 so that the inner ends 11 lie substantially transverse to the longitudinal axis of the envelope. Externally of envelope 3 the lead-in wires 7 are connected to an end eyelet 12 and side contact 13 of the base 5.

The fulminating material 10 may be of the general type disclosed and claimed in U.S. Patent 2,280,593—G. H. Meridith, issued April 21, 1942, and comprising an admixture of fine (i.e., of the order of 325 mesh or

2

finer) No. 3 grade magnesium-zirconium and potassium perchlorate powders bonded together with a suitable binder such as a 2 to 5% solution of nitrocellulose in amyl acetate. For best results, however, and particularly where the ignition filament 9 is of the diameter of the order of $7/10$ mil, it is preferred that the relative proportion of the above-named powder ingredients be within the particular ranges disclosed and claimed in U.S. Patent 2,756,577—R.M. Anderson, issued July 31, 1956, such ranges being of the order of some 60 to 90% zirconium, 1 to 8% magnesium and 9 to 35% potassium perchlorate.

To strengthen the envelope 3 and render it substantially shatter-proof on charge flashing a protective lacquer coating 14 of the type disclosed and claimed in U.S. Patent 2,791,113—R. M. Anderson, issued May 7, 1957 is applied to the outer side of the envelope, the inner side of the envelope being left bare. However, the lacquer coating may be applied to the inner side of the envelope.

15 An upper extension 17 of stem 6 carries a support rod 18 which, in turn, supports a combustible sheet 19 by means of a clip 20 clamped along its length to sheet 19 and rod 18 (FIG. 3). Support rod 18 comprises a lower portion 21 extending vertically out of stem extension 17.

25 The rod 18 is bent at right angles to lower end portion 21 to provide a horizontal offset 22 and again bent at a right angle to provide another vertical portion 23 which is clamped within clip 20. It will be noted that the rod 18 is made up of a wire which doubled back on itself 30 with both ends thereof embedded in extension 17.

The combustible sheet 19 consists essentially of magnesium with 2.5 to 3.5% aluminum, 0.2% manganese, 0.7% to 1.3% zinc, and 0.76% silicon, copper, nickel, iron and other impurities. This material is used because 35 it vaporizes more readily than, for example, aluminum or zirconium, at the ignition temperature (approximately 920° K.). The combustible sheet is approximately 1 inch by 3 inch by 8 mil. Vertical portion 23 of the support rod 18 prevents this relatively large mass of flexible material from contacting the envelope wall eliminating any danger of shattering the glass envelope.

It has been found that the combustible sheet 19 must be provided and maintained in a relatively planar shape so as to emit a maximum amount of light. When the 45 combustible material is provided in a curved or curled shape it is believed that the unconsumed material absorbs some of the energy and lower light intensities are delivered. Also, the curled or curved shapes burn irregularly and a long duration of relatively constant light output 50 cannot be maintained. Hence, to further prevent curling of the sheet 19 as it is consumed, combustion-regulating tabs 25 are provided. As shown in FIG. 2, tabs 25 are punched in spaced apart rows throughout the surface area of sheet 19 with alternate rows extending from opposite 55 sides of the sheet 19 so as to give structural rigidity to it. When the sheet 19 is ignited, the tabs 25 are more readily combustible than the body of the sheet and hence, curling is prevented since the combustion proceeds regularly on both sides of the sheet.

60 The support rod 18 is a stainless steel alloy having a coefficient of thermal expansion which closely matches the coefficient of expansion of the glass stem 6 such that when the magnesium sheet 19 is burned, the stem 6 and rod 18 do not expand differentially so as to crack the glass and allow the sheet to fall onto the envelope wall. The offset 22 is provided so that the sheet 19 will be supported substantially centrally within envelope 3. Thus, even if the sheet were to curl as it burns, no contact will be made with the envelope.

65 The clip 20 consists essentially of aluminum and prevents the unconsumed portion of the combustible sheet 19 from falling against the glass envelope 3 by acting as a

"heat sink." That is, the sheet 19, as it is being consumed, might have a tendency to burn along the junction line between the clip 20 and sheet 19 thus severing unconsumed material from the support. Because the aluminum does not ignite near the temperature of magnesium, the aluminum clip 20 remains intact and "cools" 5 that portion of the sheet 19 closely adjoining clip 20 preventing early combustion of that portion.

The lower edge of sheet 19 is supported by clip 20 in close proximity to filament 9 and primer beads 10, the lower edge being provided with serrations 24 so that sheet 19 may be readily ignited. The serrations 24 are made even more readily ignitable by coating them with primer material of approximately the same composition as primer beads 10. 10

The envelope 3 is filled with a combustion-supporting gas, the major portion of which is oxygen. However, to further control the burning of sheet 19 a gas which does not enter into the actinic reaction is also provided. While, theoretically, many gases would fulfil this function, argon or krypton is considered vastly superior to that of nitrogen, helium, or sulfur dioxide. Argon gas is preferred because it would appear that a mixture of approximately 33% argon and 67% oxygen will support combustion for a time period limited only by the amount of oxygen and combustible material present to react. This is believed to be so because the argon seems to be differentially attracted to the metal sheet present in the envelope and forms a barrier layer between the metal and the oxygen. This layer is effectively stripped away as the material is 20 consumed and only then is more metallic material exposed to oxygen.

Although a preferred embodiment of my invention has been disclosed, it will be understood that the invention is not limited to this specific instruction and arrangement of parts shown but may be widely modified within the spirit and scope of my invention as defined by the appended claim. 25

What I claim as new and desire to secure by Letters Patent of the United States is:

A flash lamp comprising a sealed light-transmitting envelope containing combustible means for emitting at least 10,000 lumens for at least 7 seconds including a relatively planar rectangular combustible sheet consisting essentially of magnesium; said sheet having primer-coated serrations at one edge and combustion-regulating tabs thereon spaced in a regular pattern throughout the surface area of the sheet; means for supporting said sheet in a longitudinal position within the envelope including a stem fused to the envelope, a stainless steel wire mounted in the stem and heat sink means fastened to said sheet and said wire thereby securing them together; said heat sink comprising an aluminum clip, a combustion-supporting gaseous mixture within said envelope consisting essentially of 67% oxygen and 33% of one of the class consisting of argon and krypton and means for igniting said combustible means. 15
